MORGAN POTTER, OF FISHKILL-ON-THE-HUDSON, NEW YORK, ASSIGNOR
TO THE MORGAN POTTER COMPANY, OF FISHKILL-ON-THE-HUDSON,
NEW YORK.

ADJUSTABLE APPLIANCE FOR LADDERS.

No. 810,170.

Specification of Letters Patent.

Patented Jan. 16, 1906.

Application filed September 21, 1904. Serial No. 225,309.

To all whom it may concern:

Be it known that I, MORGAN POTTER, a citizen of the United States, residing at Fishkill-on-the-Hudson, in the county of Dutchess and State of New York, have invented 5 certain new and useful Improvements in Adjustable Appliances for Ladders, of which the following is a specification, reference being had to the accompanying drawings, and to 10 the letters of reference marked thereon.

My invention has relation to that class of appliances for ladders which are employed at the bottom thereof for the purpose of varying the length of one of the ladder sides or rails, 15 so as to make the bottom of the ladder conform to the configuration of the ground on which it is located, thereby compelling the ladder to stand in a proper upright position, as it would upon a level foundation, though 20 it be erected on an uneven foundation.

Heretofore in this class of devices it has been proposed to cut away the material of the ladder-rail to accommodate a sliding piece and also to apply a sliding piece directly 25 against the outer face of the ladder-rail and to compel the same to bite into the wood, by both of which constructions the strength of the ladder is not only impaired, but the necessary extent of adjustment and 30 the requisite strength and reliability of the appliance fail to be attained.

The principal object of my invention is, therefore, to provide or produce a device which may be easily and quickly fitted to the 35 lower end of one of the rails of a ladder without altering or weakening the ladder, and which will be amply strong in any position to which it may be adjusted, and which will afford a degree or extent of adjustment commensurate with its size and weight and 40 commensurate with the requirements of all ordinary circumstances.

Subordinate objects are to make the device applicable to any size and shape of the 45 ladder-rail and to secure facility of adjustment and reliability of holding power at any point to which it may be adjusted.

To accomplish all of these objects and to secure other and further advantages in the 50 matters of construction, operation, and use, my improvements involve certain new and use-

ful arrangements, constructions, and combinations of parts, as will be herein first fully described and then pointed out in the claims.

In the accompanying drawings, forming 55 part of this specification, Figure 1 is a front elevation showing the bottom part of a ladder with my improved appliance mounted thereon, the adjustable foot or sliding piece being extended beyond the foot of the ladder-rail only to about one-fourth of its possible extension; and Fig. 2 is a corresponding side view. Fig. 3 is a side elevation of the base or bed plate, which is affixed to the ladder-rail, the same being shown as provided with 60 rearwardly-extending side projections to adapt it to be fitted upon a rounded rail when required. Fig. 4 is a front elevation or face view corresponding with Fig. 3. Fig. 5 shows a cross-section of a rounded ladder-rail and an end view of the base or bed plate 65 applied thereon.

In all these figures like letters of reference wherever they occur indicate corresponding parts.

A A represent the side rails of a ladder of any size and length, and these may be either flat or rounded on their exterior faces, after the usual manner of constructing ladders.

B B represent the ladder-rungs.

C is the base or bed plate of my appliance, which is to be affixed to the outside of the lower end of one of the ladder-rails. This plate is preferably made of light cast metal, and it is fixed in place by simple wood-screws 85 or by screw-bolts, as may be preferred. Wood-screws are represented at a a, and screw-bolts at b, the latter being preferably employed at the lower end, at which point the greatest strain will be brought upon the 90 bed-plate in a direction tending to dislodge it. At the lower part of the bed-plate C is a cross-bridge D, beneath which the sliding piece or adjustable foot is fitted to move, the bridge being preferably ribbed on the exterior, as shown, to contribute strength, and on the upper part of the bed-plate, on its outer face, are a series of cross serrations or ledges, (represented at c,) with which the corresponding ledges or serrations on the inner 95 face of the sliding piece at its upper portion are made to engage and lock.

To make the 100

bed-plate light without impairing its necessary strength, it may be cut out or recessed, as at *d d*.

E is the sliding or adjustable piece. As 5 will be observed, this is of considerable length as compared with the distance between the rungs. Its foot or bearing-point is somewhat extended, as represented at *e*, and at the bottom it is supplied with a slight 10 projection or lug *f*, calculated to enter a corresponding recess *g* in the lower end of the bed-plate when the foot *e* is at its highest 15 point or on a level with the bottom of the rail. The inner face of the slide *E* is serrated or notched from its upper end downward for 20 about half the length of the piece, as at *h*, to engage with the serrations *c*, and the slot *i* in the slide *E* receives the bolt *k*, which latter is entered through the inner face of the ladder- 25 rail and through the perforation provided for it in the bed-plate. The lower face of the foot *e* is preferably serrated, as shown, to afford a good hold on the ground.

The parts *C* and *E* are locked together by 30 the engaging serrations or ledges and held immovable at the point to which the slide may be adjusted by any suitable form of nut—as, for instance, a thumb-nut *F* on the bolt *k*.

35 The slide *E* is made as thin and light as may be consistent with its necessary strength, and ample strength to resist sidewise pressure on the ladder is contributed by supplying the slide on its outer face with marginal ledges or projections, as shown at *l l*. These ledges ride under and bear against the inner 40 face of the bridge *D*.

From a consideration of the foregoing it 45 will appear that the sliding piece or adjustable foot is firmly held by the bridge and by the holding bolt and nut and that the bridge in no way interferes with the vertical adjustment, the only limit to the extent of vertical adjustment being the length of the slot *i*. 50 The bridge dispenses with the necessity for a second holding or locking bolt, which would limit the extent of adjustment, and yet it is located so low relatively that it can clamp the slide *E* quite snugly and still permit the separation of the upper portion of the parts *C* and *E* sufficiently to allow their serrations to pass over each other in the act of adjusting the device. The marginal ribs *l* on the outer face 55 of the slide *E* fit in the corners of the bridge *D*, take up wear, and strengthen the slide without requiring it to be made unnecessarily heavy.

60 The bed-plate is intended to be fastened upon the ladder-rail without altering the latter and without cutting into it or otherwise rendering it weak or subjected to unnecessary

wear. If the outer face of the ladder-rail be flat or plain, the flat inner face of the bed-plate fits against it; but if the outer face of the ladder-rail be rounded, as indicated in Fig. 5, then small lugs or projections, as *m m*, on the back of plate *C* are employed to make a firm bearing for the plate on the rounded rail, as will be readily understood.

The operation of the device is to afford a bearing for the foot of the ladder same as if the latter stood on a level foundation, and this with obvious advantages in raising and using the ladder.

Being constructed and arranged substantially in accordance with the foregoing explanations, the improved device will be found to admirably answer the purposes and objects of the invention previously set forth.

Having now fully described my invention, what I claim as new herein, and desire to secure by Letters Patent, is—

1. In a device of the character herein set forth, a sliding piece slotted at its upper part and having serrations on its back and smooth at its lower part, a metallic bed-plate having serrations on its front at its upper part and smooth at its lower part, and having a bridge for crossing the lower portion of the sliding piece, a bolt passing through the serrated part of the bed-plate and through the slot in the sliding piece, the bolt being located above the cross-bridge, and a nut on the bolt, the parts being combined and arranged substantially as shown and described. 95

2. In a device of the character herein set forth, the combination with the metallic bed-plate, of rearwardly-extending side lugs for bearing on the rounded surface of a ladder-rail, substantially as and for the purposes set forth. 100

3. The combination with the metallic bed-plate having its outer face serrated at its upper part and smooth at its lower part; of the sliding piece having its inner face serrated at its upper part and smooth at its lower part and its body slotted longitudinally through the serrations, a locking-bolt passing through said slot and through the bed-plate, a thumb-nut on the bolt, longitudinal marginal ribs on the outer face of the sliding piece throughout its lower portion, and a cross-bridge on the bed-plate embracing said sliding piece and into whose angles said marginal ribs bear at points below the bolt. 115

In testimony whereof I have signed my name to this specification in the presence of two subscribing witnesses.

MORGAN POTTER.
